(57) **CLAIM**

The ornamental design for a heated water hose, as shown and described.

DESCRIPTION

FIG. 1 is a front, top perspective view of the first embodiment of a heated water hose, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, top perspective view of the second embodiment of a heated water hose, showing my new design;

FIG. 10 is a rear, bottom perspective view thereof;

FIG. 11 is a front elevational view thereof;

FIG. 12 is a rear elevational view thereof;

FIG. 13 is a left side view thereof;

FIG. 14 is a right side view thereof;

FIG. 15 is a top plan view thereof; and,

FIG. 16 is a bottom plan view thereof.

The dashed broken lines in the figures are for the purposes of illustrating portions of the heated water hose that form no part of the claimed design.

The short-short-long dashed broken lines immediately adjacent to the claim area for the purposes of illustrating the boundaries of the heated water hose, and form no part of the claimed design.
